UNITED STATES PATENT OFFICE.

MORITZ EISNER, OF NEW YORK, N. Y.

INCANDESCENT GAS-BURNER.

SPECIFICATION forming part of Letters Patent No. 591,036, dated October 5, 1897.

Application filed April 2, 1897. Serial No. 630,418. (No model.)

To all whom it may concern:

Be it known that I, MORITZ EISNER, a citizen of the United States, and a resident of New York city, in the county of New York 5 and State of New York, have invented certain new and useful Improvements in Incandescent Gas-Burners, of which the following is a specification.

My invention relates to the construction of 10 burners for incandescent gas-lamps, and its objects are directed especially to the purpose of promoting the admixture of the gas and air supplied to the burner; to which end it consists of certain novel features, including 15 a hollow globe, forming a gas and air mixing chamber, with lateral air-inlet openings in its lower part, a gas-supply nozzle connected to the bottom of the globe, a draft-tube connected to the top of the globe, an air-controlling valve encircling the lower part of the globe, with openings adapted to register with said air-inlet openings, and a ball suspended in the center of the globe to form a deflector of the mixed gas and air ascending 25 through the mixing-chamber to the draft-tube, and thence to the tip of the burner.

My invention is illustrated in the accompanying drawings, in which—

Figure I represents a vertical central section of the burner embodying the same. Fig. II represents a side elevation thereof, omitting the burner-tip and its accessories. Fig. III represents a horizontal section of the burner, taken in the plane between two sections 30 constituting the globe or mixing-chamber. Fig. IV represents a partial side view and partial vertical section of the burner with the ball-deflector in position therein. Fig. V represents a horizontal section corresponding to Fig. III, including the ball-deflector.

Similar letters of reference indicate similar parts.

The letters A B indicate two hemispherical 45 sections composing the globe, which constitutes the gas and air mixing chamber of the burner.

The letter C indicates the lateral air-inlet openings of the globe, the location of which 50 is at the lower part thereof.

D indicates the air-controlling valve, which

is fitted on and encircles the lower part of the globe opposite to its said air-inlet openings and which has openings e at suitable points for adapting the same to register with the 55 openings of the globe.

The letter F indicates the gas-supply nozzle, which is connected to the lower part of the globe, and G the draft-tube, which is connected to the top of the globe, said draft-tube being surmounted by the tip S, forming 60 the burner proper.

The letter H indicates the ball-deflector, (see Figs. IV and V,) which is suspended in the center of the globe A B by means of wires I, the ends of which are fitted in the horizontal joint between the sections of the globe.

In the use of the burner the gas and air are mixed in the chamber formed by the globe-sections A B, and thence ascend through 70 the draft-tube G to the tip S, which is the point of combustion, and it will be readily understood that by reason of the globular shape of the mixing-chamber, as well as the ball-deflector H, a very effective admixture 75 of the gas and air is obtained. It should be remarked that instead of a spherical shape the globe A B may be of elliptical or other approximate shape, one and the important feature thereof and of its interiorly-arranged 80 ball-deflector being the interposition of these parts between the gas-supply nozzle F and the draft-tube G, leading to the tip of the burner.

The valve D is movable horizontally on 85 that part of the globe which it encircles and may be provided with a knob o, Fig. II, to facilitate its adjustment, and in order to arrest any impurities in the gas from ascending to the tip of the burner the draft-tube may 90 be provided with a sieve or strainer n at or about its junction with the mixing-chamber.

What I claim as my invention, and desire to secure by Letters Patent, is—

In an incandescent gas-burner, a hollow 95 globe forming a gas and air mixing chamber constructed in two horizontally-divided sections, with lateral air-inlet openings in its lower part, a gas-supply nozzle connected to the bottom of the globe, a draft-tube connected to the top of the globe, an air-controlling valve encircling the lower part of the 100

globe with openings adapted to register with
said air-inlet openings thereof, a ball sus-
pended in the center of the globe, forming a
deflector of the mixed gas and air, and the
5 ball-supporting wires fitted in the joint be-
tween the globe-sections substantially as
herein described.

Signed at New York city, in the county of
New York and State of New York, this 30th
day of March, A. D. 1897.

MORITZ EISNER.
